UNITED STATES PATENT OFFICE.

WILLIAM SHERMAN BROWN, OF KNOXVILLE, TENNESSEE.

STEAM-ENGINE VALVE-GEAR.

1,076,406.

Specification of Letters Patent. Patented Oct. 21, 1913.

Application filed March 24, 1913. Serial No. 756,500.

To all whom it may concern:

Be it known that I, WILLIAM SHERMAN Brown, a citizen of the United States, residing at Knoxville, in the county of Knox and State of Tennessee, have invented a new and useful Improvement in Steam-Engine Valve-Gears, of which the following is a specification, reference being had to the accompanying drawing.

10 My improvement relates particularly to mechanism for transmitting motion from the crank of a drive wheel of a steam locomotive to the distributing valve which admits steam to the cylinder.

15 The object of the improvement is to provide a construction which is simple, has the parts accessibly located, and which avoids irregularity of valve action due to lost motion or "pounding" at the crank.

20 This improvement is applicable to the mechanism described by my United States Patent No. 1,033,532, granted July 23, 1912, for "steam-engine valve-gear."

In the accompanying drawings, Figure 1 is a side elevation, portions being broken away, showing my improvement applied to one side of a locomotive; Fig. 2 is a plan of a portion of the mechanism shown by Fig. 1; Fig. 3 is a section on the line, 3—3, of Fig. 2, looking toward the right; Fig. 4 is a section on the line, 4—4, of Fig. 2, looking in the direction of the arrow; Fig. 5 is a plan of the bridge upon which the segment is seated; Fig. 6 is a side elevation of said bridge.

25 Referring to said drawings, 1 is the cylinder, 2 is the valve chest, 3 is the slide valve located within said chest, and 4 is the usual valve stem extending through said chest. The ordinary piston, 5, is located within said cylinder, and has applied to it the ordinary piston rod, 6, which is joined to the ordinary cross-head, 7, confined between the usual horizontal, parallel guide-bars, 8, supported at their rear ends by the guide yoke extension, 15. To said cross-head is coupled one end of the usual connecting rod or pitman, 9, the other end of said rod being coupled to the usual main crank, 10, carried by a drive wheel, D. On the main crank, 10, is rigidly mounted an auxiliary crank, 12, standing 90 degrees forward of the main crank. To said auxiliary crank is coupled one end of the auxiliary pitman rod, 13. A bridge, B, is located

above the frame, A, and extends from the ordinary guide-yoke, 14, and guide-yoke extension, 15, to the cross beam or plate, 16, and is secured to said guide-yoke and to said cross-beam by means of bolts, 17. Said bridge is in the form of a plate having its length horizontal and being turned to bring its long edges into an upright plane. At its rear end, the bridge has a lateral extension, 18, resting against the cross-beam, 16, and receiving said bolts, 17. At its forward end the bridge has a transverse extension, 19, reaching to both sides of the body of the bridge and resting against the guide yoke, 14, and the guide yoke extension, 15, and receiving said bolts, 17. The innermost of said bolts extends through the transverse extension, 19, and the guide yoke, 14, while the others of said bolts extend through the transverse extension, 19, and through the guide yoke, 14, and the guide yoke extension, 15. On the forward portion of the transverse extension, 19, and integral therewith is an ear, 20, which is directed rearward; and on the inner portion of said transverse extension is another ear, 21, also directed rearward and located horizontally opposite the ear, 20. Each of said ears has a bearing, 22, receiving the ends of a shaft, 23. On said shaft is a bell crank or rocking member, C, preferably rotatable on said shaft, the latter being held immovably in its bearings. Said bell crank has two approximately horizontal arms, 24, and a depending arm, 25. The latter arm is coupled to the valve-stem, 4. By rocking the bell crank, the valve stem is reciprocated.

30 An approximately upright link, 26, has its upper end coupled to the arms, 24, of the bell crank, while its lower end is coupled to the forward end of the auxiliary pitman rod, 13, both ends of said link being forked to receive said rod and said arms, as shown in the drawings. Said arms, 24, are also forked to receive the upper ends of the link, 26.

35 On the upper edge of the bridge, B, are horizontal bosses, 27. A segment or link, E, has at each end a foot, 28, resting upon one of the bosses, 27; and bolts, 29, extend through said feet and said bosses for securing said segment rigidly upon the bridge, B. Said segment is in the form of a plate having its body set in an upright plane.

40 In the segment is a curved slot, 30, in

which rests a slide block, 31, to which is coupled the upper end of an approximately upright link, 32. The lower end of said link is coupled to the auxiliary pitman rod, 13, by a bolt, 33. The slot, 30, is preferably made concentric with an axis which approximately intersects a line which is an extension of the cylinder axis and cuts the axis of the drive wheel, D; and the length of said link is such as to allow the axis of said bolt to become coincident with the axis to which said slot is concentric. An approximately horizontal link, 34, is coupled by its forward end to the slide block, 31, and by its rear end to the arm, 35, which is rigid on a rock shaft, 36, supported in bearings, 37. On said rock-shaft is an arm, 38, to which is coupled a rod, 39, which is in turn coupled to the ordinary reversing lever, 40, working on a sector or quadrant, 41.

In operation, the slide block, 31, is set in any desired position in the slot, 30, by means of the reversing lever, and while said block is so set, the link, 32, oscillates on said block with each reciprocation of the auxiliary pitman rod, the axis of the bolt, 33, moving in an arc in which lies the axis to which the slot, 30, is concentric; and the distance between the wrist of the auxiliary crank, 12, and the bolt, 33, is such as to bring the axis of said bolt into the slot axis when the drive wheel is on either the front or the rear quarter. In Fig. 1, it is shown on the front quarter, the auxiliary crank being on the top. During each such reciprocation, said auxiliary pitman rod rocks bodily with the axis of the bolt, 33, as a fulcrum. This involves the rising and falling of the forward end of said auxiliary rod, and during such movement of said end of said rod, the link, 26, is forced up and down and such movement of said link causes the rocking of the bell crank, C, and the reciprocation of the valve stem, 4.

The gear is reversed by throwing the reversing lever across the center in the usual manner, and the opening of the valve is varied by moving the slide block nearer to or farther from the middle of the slot, 30, this being accomplished by the aid of suitable notches (not shown) on the reversing lever sector. When the slide block is on the middle of said slot, the valve motion is reduced to the extent of the "lead".

The drawings have been copied from larger working drawings used in applying my improvement to a railway freight locomotive having a piston stroke of 30 inches and having a maximum valve travel of $5\frac{1}{2}$ inches and a lead of three sixteenths of an inch. The radius of the auxiliary crank, 12, (measuring from the driver axis) is 8 and $\frac{1}{2}$ inches. The distance from the auxiliary crank along the auxiliary pitman rod, 13, to the axis of the bolt, 33, is 74 and $\frac{3}{2}$ inches.

From the latter point on said pitman rod to the link, 26, is 10 and $\frac{1}{2}$ inches. The length of the link, 32, is 35 and $\frac{11}{16}$ inches, and that, as already described, is also the radius of the curved slot, 30, in the segment, E; and the center of said curved slot coincides with the axis of the bolt, 33, when the auxiliary crank is on the upper quarter or the lower quarter, at which time said bolt is one and five sixteenths inches below the level of the driver axis and the cylinder axis (the "working line" or "center line of motion"). The length of the link, 26, is 32 inches. The height of the axis or fulcrum of the bell crank or rocking member, C, above the level of the center line of motion is 32 and $\frac{2}{3}$ inches. The length of the arms, 24 and 25, of the bell crank is 12 and $\frac{1}{8}$ inches. The rocking member, C, is not a true bell crank, its angle being less than ninety degrees—72 degrees.

When the engine is in forward motion and the main crank is on the back center and the auxiliary crank on the upper quarter, the arm, 24, is 2 and $\frac{1}{2}$ degrees back of a vertical line cutting the fulcrum, and the arms, 24, are 15 and $\frac{1}{2}$ degrees below a horizontal line cutting the fulcrum. When the slide block, 31, is set for full valve travel (5 and $\frac{1}{2}$ inches), the forward travel of the arm, 25, from the position mentioned is 7 and $\frac{1}{2}$ degrees and the back travel of said arm from said position is 19 degrees, and the arms, 24, travel downward and upward correspondingly. Thus the larger portion of the travel of the rocking member arms is within the 90 degree angle formed by said vertical and said horizontal lines. These relative proportions and positions of the various parts of the mechanism produce the desired quick movement of the valve during the opening and closing and also produce equalized travel of the valve over the port during the forward motion and during the backward motion. Fig. 1 of the drawings shows the slide block on the center, while the port is shown open full. This is done because the very small actual port opening, when the slide block is so set, can not be shown.

It is to be observed that my improvement eliminates from the valve mechanism the eccentric and also all parts having a high velocity. No part of the valve mechanism is connected to the connecting rod nor the cross-head. Movement is transmitted to the valve stem from the wrist of the auxiliary crank and said wrist travels in a relatively small circle. Thus the movement of the auxiliary rod and the links, 26, and 32, are through relatively short ranges. Furthermore, it is to be noted that lost motion due to wear at the wrist of the auxiliary crank will chiefly modify the lengthwise movement of the auxiliary pitman, 13, while the

movement transmitted through the link, 26, is approximately at right angles to said auxiliary pitman. Hence the modification of the longitudinal movement of said pitman 5 is substantially not transmitted to said link. And it will be seen that such modification of the rocking movement of the auxiliary pitman due to wear at the wrist of the auxiliary crank will affect the link, 26, in minimized form, because the portion of the auxiliary pitman between the axis, 33, and the link, 26, is much less than between said axis and the wrist of the auxiliary crank. In this connection it is to be remembered that wear 10 by the auxiliary crank wrist in the auxiliary pitman is chiefly in the direction of the length of said pitman. Such wear produces what is termed lost motion or "pounding" at the crank.

20 I claim as my invention:

1. In a steam engine valve gear, the combination of an adjustable, horizontal segment, a slide block on said segment, means for moving said block, an auxiliary crank, 25 an auxiliary rod coupled to said crank, and two approximately upright links, each having its lower end coupled to the auxiliary rod and one having its upper end coupled to said slide block and the other having its 30 upper end in operative relation with the distributing valve, substantially as described.

2. In a steam engine valve gear, the combination of an adjustable, horizontal segment, a slide block on said segment, means for moving said block, a bell crank in operative relation with the distributing valve, 35 an auxiliary crank, an auxiliary rod coupled to said crank, and two approximately upright links each having its lower end coupled to the auxiliary rod and one having its upper end coupled to said slide block and the other having its upper end coupled to said bell crank, substantially as described.

45 3. In a steam engine valve gear, the combination of an approximately horizontal bridge, a horizontal segment adjustable on said bridge, a slide block on said segment, means for moving said block, an auxiliary crank, an auxiliary rod coupled to said crank, and two approximately upright links, 50 each having its lower end coupled to the auxiliary rod and one having its upper end coupled to said slide block and the other having its upper end in operative relation 55 with the distributing valve, substantially as described.

4. In a steam engine valve gear, the combination of an approximately horizontal bridge, a horizontal segment adjustable on said bridge, a slide block on said segment, means for moving said slide block, a bell crank in operative relation with the distributing valve, 60 an auxiliary crank, an auxiliary rod coupled to said crank, and two approximately upright links each having its lower

iliary rod coupled to said crank, and two 65 approximately upright links each having its lower end coupled to the auxiliary rod and one having its upper end coupled to the slide block, and the other having its upper end coupled to the bell crank, sub- 70 stantially as described.

5. In a steam engine valve gear, the combination of a bracket, a bell crank hinged to said bracket and being in operative relation with the distributing valve, a slide block, 75 adjustable means for supporting said slide block, means for moving said slide block, an auxiliary crank, an auxiliary rod, and two approximately upright links each having its lower end coupled to said auxiliary rod and one having its upper end coupled to said slide block and the other having its upper end coupled to said bell crank, substantially as described.

6. In a steam engine valve gear, the combination of two stationary members rigid on the frame, a bridge having its rear end secured to one of said stationary members and having its forward end secured to the other of said stationary members, a bell 90 crank supported by said bridge and being in operative relation with the distributing valve, a horizontal segment adjustable on said bridge, a slide block on said segment, means for moving said block, an auxiliary 95 crank, an auxiliary rod coupled to said crank, and two approximately upright links each having its lower end coupled to the auxiliary rod and one having its upper end coupled to said slide block and the other having its upper end coupled to said bell 100 crank, substantially as described.

7. In a steam engine valve gear, the combination of an approximately horizontal bridge having bearings integral therewith, 105 a segment adjustable on said bridge, a slide block on said segment, means for moving said slide block, a bell crank in operative relation with the distributing valve and supported by said bearings, an auxiliary crank, 110 an auxiliary rod coupled to said crank, and two approximately upright links each having its lower end coupled to the auxiliary rod and one having its upper end coupled to the slide block and the other having its 115 upper end coupled to the bell crank, substantially as described.

8. In a steam engine valve gear, the combination of an approximately horizontal bridge having a transverse extension and 120 bearings integral therewith, a segment adjustable on said bridge, a slide block on said segment, means for moving said slide block, a bell crank in operative relation with the distributing valve and supported by said 125 bearings, an auxiliary crank, an auxiliary rod coupled to said crank, and two approximately upright links each having its lower

end coupled to the auxiliary rod and one having its upper end coupled to the slide block and the other having its upper end coupled to the bell crank, substantially as described.

5 In testimony whereof I have signed my name, in presence of two witnesses, this 17th

day of March, in the year one thousand nine hundred and thirteen.

WILLIAM SHERMAN BROWN.
